UNITED STATES PATENT OFFICE.

CHARLES NICHOLSON, OF HATFIELD, NEAR DONCASTER, ENGLAND.

CARRIAGE-WINDOW.

No. 850,958.

Specification of Letters Patent.

Patented April 23, 1907.

Application filed January 23, 1906. Serial No. 297,516.

To all whom it may concern:

Be it known that I, CHARLES NICHOLSON, a subject of the King of Great Britain and Ireland, residing at The Leylands, Hatfield, 5 near Doncaster, in the county of York, England, have invented certain new and useful Improvements in Railway-Carriage and other Windows, of which the following is a specification, reference being had therein to the accompanying drawings.

This invention relates to railway-carriage and other windows which are raised or lowered by means of a strap.

I propose to secure in the window-frame 15 two rollers between which the window-strap passes, and these rollers are provided with lips or projecting ribs between which the strap can be gripped, so as to support the window in any position. The rollers are arranged to grip the strap between their projecting lips automatically on its release, while on pulling down the strap the lower roller is turned back slightly, allowing the strap to be drawn down freely and the window to be raised. On releasing the strap, 25 however, the lower roller turns in a little and grips the strap immediately. To provide a more effective grip, the lip or rib may be roughened or serrated.

To allow the window to be lowered, the lower roller is provided with a finger-piece, on pressing which the roller is turned back slightly and releases the strap and window, which falls to the bottom, or until the finger-piece is released, when the strap is at once gripped and the window held in the required position.

In order that this invention may be more readily understood, reference is had to the 40 accompanying sheet of drawings, in which—

Figure 1 is an elevation of a window provided with my improvements, and Figs. 2 and 3 are sections showing the window-strap gripped and released.

On the window-frame *a* are secured the 45 brackets *b*, carrying the two rollers *c* and *d*, the roller or bar *c* being fixed in the brackets, while *d* can turn. Both rollers are provided with the toothed or serrated ribs *e*, which project toward each other and are placed 50 slightly toward the front or inner side of the window. The strap *f*, supporting the window in the usual manner, passes between the two rollers, and on pulling the strap to raise the window the lower roller is slightly turned 55 into the position shown in Fig. 3, allowing the strap to pass freely; but on releasing the strap the roller is turned back into the position shown in Fig. 2, and the strap is firmly gripped between the serrated ribs *e*, thus 60 holding the window in any desired position.

To release the strap and allow the window to fall, the lower roller *d* is turned by the finger-piece *g*, which on being pressed in, as shown in Fig. 3, releases the strap. 65

What I claim as my invention, and desire to secure by Letters Patent, is—

In means for securing the straps of railway-carriage and other windows, a fixed upper roller and a rotating lower roller, serrated 70 ribs on both rollers between which the strap is gripped and a finger-piece on the lower roller turning it to release the strap, substantially as herein described.

In testimony whereof I affix my signature 75 in presence of two witnesses.

CHARLES NICHOLSON.

In presence of—

LUTHER J. PARR,
CHAS. N. DANIELS.
